UNITED STATES PATENT OFFICE.

GEORGE FRED DRIEMEYER, OF ST. LOUIS, MISSOURI, ASSIGNOR TO COMMONWEALTH STEEL COMPANY, OF MADISON COUNTY, ILLINOIS, A CORPORATION OF NEW JERSEY.

LOCOMOTIVE FRONT-END STRUCTURE.

Application filed January 10, 1927. Serial No. 180,246.

My invention relates to railway rolling stock and consists of an improved front end structure for locomotives.

The main object of my invention is to provide a single member adapted to be applied to the front end of the side frames or locomotive bed, said member preferably including other elements of the locomotive such as the cylinder saddle, the cylinders, the front deck plate, the pilot beam, and front truck mounting elements.

Present locomotive construction results in a shallow depth of the frame at the front end due to the provisions usually made for bolted the cylinders thereto and for clearing the front truck. Preferably my invention is embodied in a one-piece casting with the parts mentioned formed integrally therewith. By making the cylinders and saddle integral with the casting, I eliminate the labor and parts required for assembling separate elements and provide greater strength than can be obtained in the assembled structure.

In the accompanying drawings illustrating my invention—

Figure 1 is a side elevation of my front end member showing the same applied to the forward end of a locomotive bed or side frame and mounted upon a pony truck.

Figure 2 is a top view of one longitudinal half of the same structure.

Figure 3 is a vertical section through one transverse half of the locomotive side frame showing the adjacent portion of my front end in elevation. The same is taken on line 3—3 of Figure 2.

Figures 4, 5 and 6 are side elevations of various modifications in the construction of my front end member whereby it is adapted to be secured to the locomotive frame in different ways.

In the construction illustrated in Figures 1, 2 and 3, the front driver of the locomotive is indicated at 1 and the side frame of the locomotive is indicated at 2, the same terminating just beyond the pedestal for the front driver and at this portion preferably having top and bottom flanges 3 and 4 which extend inwardly.

My front end member is shown as a one-piece casting having at its rear end side pieces 5 adapted to be seated between the said frame flanges 3 and 4 and to be bolted to the side frame as indicated at 6. Transverse elements

7 and 8 connect the portions of the end casting which are bolted to the side frames 2 and the lower one of these elements includes integral pocket forming elements 9 for mounting the radius bar 10 of the pony truck, indicated by the wheels 11.

In front of the locomotive side frames 2, the side pieces of the casting have cylinders 12 formed integrally therewith and preferably the steam chambers, such as piston valve chambers 13 or steam chests, are formed integrally with the cylinders. This portion of the casting also includes the boiler saddle 14 and suitable steam passages 15 leading from the cylinders through the saddle.

In front of the cylinder and saddles the casting forms a front deck plate 16 which has an integral truck pivot bearing 17 and the deck plate terminates in a pilot beam 18 extending transversely of the frame and in front of the cylinders.

In the structure illustrated in Figure 4, the locomotive frame 20 has upper and lower members 21 and 22 in front of the front driver pedestal and the front end casting 23 has rearwardly projecting members 24 and 25 aligned with frame elements 21 and 22 and welded thereto as indicated at W. It will be understood that the front end casting includes cylinders 26, saddle 27, steam chambers 28 and guide elements 29 for the front truck radius rod 30, all similar to the more detailed structure shown in Figures 1 and 2.

In the modification illustrated in Figure 5, the locomotive side frame 31 terminates in front of the front driver pedestal in longitudinal arms 32 and 33 and the rear end of the front end casting terminates in arms 34 adapted to overlap the side frame arms 32 and 33 and to be bolted thereto as indicated at 35.

In the modification illustrated in Figure 6, the locomotive side frame 36 terminates at the rear of the pedestal of the front driver 37 and the pedestal 38 for this driver forms the rear part of the front end casting, the same extending to the right of the portion illustrated in the drawing and including the cylinders and other parts referred to in connection with Figures 1 and 2.

In this construction the casting may be welded to the locomotive side frame as indicated at W or the upper and lower portions of the side frame and end casting between pedestals 38 and 39 may be overlapped and

bolted or riveted together similar to the arrangement shown in Figure 5. In this construction I show a brake cylinder fulcrum bracket 40 formed integral with the casting 5 adjacent to the radius bar pocket 41. This element and other desirable elements may be advantageously added to the various front end castings described by me.

In each embodiment of my invention, a 10 member forming the front end of the frame has formed integrally therewith one or more other locomotive elements hitherto separately secured to the frame and the construction described herein makes possible the attainment 15 of the objects set forth at the beginning of my specification.

Other modifications in the form of the front end member and in the method of attaching to the locomotive frame may be made 20 without departing from the spirit of my invention and I contemplate the exclusive use of such modifications as are included in the scope of my claims.

I claim:

- 25 1. A locomotive front end member forming a forward extension of and detachable from the locomotive frame and including integral cylinders.
2. A locomotive front end member applicable to the locomotive side frames and forming a forward extension thereof and including integral steam cylinders and boiler saddle.
3. A detachable front end member applicable to the locomotive frame and embodying steam cylinders, a front deck plate, and front truck mounting elements all formed integrally.
4. A locomotive front end casting applicable to a locomotive bed or frame and forming a forward extension thereof and including integral steam cylinders.
5. A locomotive front end casting applicable to a locomotive bed or frame and forming a forward extension thereof and including integral steam cylinders and boiler saddle.
6. A locomotive front end casting applicable to a locomotive bed or frame and including integral steam cylinders, a boiler saddle, and a front end deck plate.
7. A locomotive front end casting applicable to a locomotive bed or frame and including integral steam cylinders, a boiler saddle, a front end deck plate, and a pilot beam extending across the front of the cylinders.
8. In a locomotive front end casting, side pieces, a pilot beam extending across the ends of and beyond said side pieces, and cylinders formed integrally with said side pieces and spaced from said pilot beam.
9. A locomotive front end casting comprising spaced side pieces each adapted to be connected at one end to the side frames of a locomotive bed, cylinders integral with said side pieces, and a pilot beam extending across

the opposite ends of said side pieces and beyond the ends of said cylinders.

10. A locomotive front end casting comprising spaced side pieces adapted to be connected at one end to the side frames of a locomotive bed, cylinders integral with said side pieces, and a deck plate between said side pieces near the front of said cylinders.

11. A locomotive front end casting comprising spaced side pieces adapted to be connected at one end to the side frames of a locomotive bed, cylinders integral with said side pieces, a boiler saddle between said cylinders, and a pilot beam across the ends of said side pieces in front of said cylinders and saddles.

12. A locomotive front end casting comprising spaced side pieces adapted to be connected at one end to the side frames of a locomotive bed, cylinders integral with said side pieces, a boiler saddle between said cylinders, a deck plate connecting said side pieces in front of said saddle, and a pilot beam across the ends of said side pieces in front of said deck plate.

13. A locomotive front end casting comprising spaced side pieces adapted to be connected to the side frames of a locomotive, cylinders, and transverse elements connecting said side pieces and forming a pilot truck.

14. A locomotive front end casting comprising spaced side pieces adapted to be connected to the side frames of a locomotive, cylinders on said side pieces, transverse elements connecting said side pieces and forming a deck plate, and a pilot truck pivot bearing below said deck plate.

15. In a locomotive, side frames each terminating adjacent to its forward driver pedestal and having inwardly turned top and bottom flanges near their ends, a front end casting having side pieces fitting said side frames between said flanges and extending beyond said side frames and including locomotive elements projecting laterally beyond said side frames.

16. In a locomotive, side frames each terminating adjacent to its forward driver pedestal; and an integral end member secured to said side frames and forming a forward extension thereof and embodying cylinder, boiler saddle and front deck plate members, and a front truck supporting said member.

17. A locomotive front end casting adapted to be applied to and to form a forward extension of a locomotive bed or side frames and including steam cylinders and steam valve chambers formed integrally therewith.

18. A locomotive front end casting adapted to be applied to and to form a forward extension of a locomotive bed or side frames and including a boiler saddle with steam valve chambers formed integrally therewith.

19. A locomotive front end casting adapted to be applied to and to form a forward ex-

- tension of a locomotive bed or side frames and including a boiler saddle with steam cylinders and steam valve chambers formed integrally therewith.
- 5 20. A locomotive front end casting adapted to be applied to and to form an extension of a locomotive bed or side frames and including steam cylinders, steam valve chambers therefor, a front deck plate, and a pilot mounting 10 member, all formed integrally.
21. A locomotive front end casting adapted to be applied to and to form an extension of a locomotive bed or side frames and including a boiler saddle, steam cylinders, steam valve 15 chambers therefor, a front deck plate, and a pilot beam, all formed integrally.
22. A locomotive front end casting applicable to and forming a forward extension of a
- locomotive bed or frame and including a boiler saddle, a deck plate, and a pilot beam all 20 formed integrally.
23. A locomotive front end member applicable to the locomotive frame and including a steam cylinder and a pilot beam formed 25 integrally therewith.
24. In a locomotive front end casting, a steam cylinder, a pilot beam in front of said cylinder and formed integrally therewith, and an arm, for attachment to the main frame of a locomotive, extending rearwardly from 30 said cylinder and formed integrally therewith.

In testimony whereof I hereunto affix my signature this 29th day of December, 1926.

GEORGE FRED DRIEMEYER.
